UNITED STATES PATENT OFFICE.

HERBERT L. LITCHFIELD, OF SOUTHBRIDGE, MASSACHUSETTS.

SHUTTLE-THREADING MEANS.

979,865.

Specification of Letters Patent. Patented Dec. 27, 1910.

Application filed January 14, 1910. Serial No. 538,104.

To all whom it may concern:

Be it known that I, HERBERT L. LITCHFIELD, a citizen of the United States, and resident of Southbridge, county of Worcester, State of Massachusetts, have invented an Improvement in Shuttle-Threading Means, of which the following description, in connection with the accompanying drawing, is a specification, like characters on the drawing representing like parts.

This invention relates to loom shuttles of the type wherein the thread is delivered through a tubular eye the outer end of which is located at the side of the shuttle, the thread being led from the bobbin recess into the tubular eye through an aperture made in the wall thereof which communicates with an upright recess made in the shuttle wood. In shuttles of this type the threading is often effected by sucking in the thread through the eye, but this is very objectionable on the score of health, and in some States laws have been passed prohibiting such use of shuttles. This sucking in of the thread is also objectionable when the yarn or thread is dyed, as in some instances the dye used is poisonous and sooner or later affects the health of the weavers.

My present invention has for its object the production of improved and novel means for threading shuttles provided with tubular eyes, whereby the objections above stated are entirely overcome, and the construction of the device greatly simplified.

It has been proposed heretofore to provide the shuttle with a tubular eye curved in the direction of its length, and with such eye a threading member is used consisting of a spirally coiled spring wire. The thread is given a turn or two about the coiled wire and then the leading end of the latter is inserted in the inner end of the curved eye and pushed downward through it, pulling the thread along through the eye. The great objection to this arrangement lies in the very practical difficulty of boring a longitudinally curved hole in the shuttle wood to receive the eye, and if such a hole can be made in thereafter inserting and firmly securing the eye therein.

In my present invention the shuttle is provided with a straight, tubular eye, the bottom of the bore or thread passage thereof being upwardly beveled or inclined to the inner end of the thread inlet or aperture. Preferably the eye is screw-threaded exter-

nally, not only so that it can be screwed into the straight hole drilled in the shuttle wood, but also so that the eye can be adjusted rotatively to vary the drag or tension upon the eye. In connection with the eye so constructed I use a threader comprising a thin, resilient and flexible shank having a thread-engaging hook or barb at its free end.

To thread the shuttle the threader is inserted in the eye at the outer end thereof and as it is pushed inward its leading end engages the beveled part of the thread passage and the shank is thereby deflected and turned to pass readily out of the thread-inlet or aperture of the eye, and finally rises high enough for the weaver to take a turn or two of the thread around the shank below the hook or barb. The threader is now drawn backward through and out of the eye, pulling the thread with it and the shuttle is threaded.

The novel features of my invention will be fully described in the subjoined specification and particularly pointed out in the following claims.

Figure 1 is a perspective view, partly broken out, of the thread-delivering end of a shuttle provided with an eye embodying a part of my present invention; Fig. 2 is a transverse section on the line 2—2, Fig. 1, showing the novel structure of the delivery-eye, and the threader therein, to illustrate the deflection of the leading end of the threader by the beveled part of the thread-passage in the eye; Fig. 3 is a similar view but showing a slightly different form of delivery-eye.

Referring to Fig. 1 the shuttle body 1, bobbin recess 2, vertical recess or socket 3 leading downward into the shuttle wood from the top of the shuttle adjacent the bobbin recess and separated therefrom by the transverse wall 4 having an upright slot 5 for the passage of the thread, and the longitudinal groove 6 in the thread-delivering side of the shuttle, may be and are all of substantially well known construction. The shuttle wood is bored transversely, at 7, Fig. 2, to intersect the recess 3 and to receive the tubular delivery-eye, and in Figs. 1 and 2 this eye is shown as a straight body portion 8, externally threaded at 9 to screw into the hole 7, the body being nicked at 10 to be engaged by a screwdriver or other suitable tool. The body 8 is drilled longitudinally for a portion of its length to form a thread-

passage 11 having the outer end or mouth 12 preferably rounded, Fig. 2, to present a smooth surface for the thread T to draw across. A part of the body is cut off at 13, 5 and provided with a thread-inlet or aperture 14, and the bottom of the passage 11 is inclined or beveled at its inner end at 15 to meet the inlet 14 at the end farthest from the mouth 12. In its general structure this 10 delivery-eye is substantially what is known as the "Thompson" eye shown in United States Patent No. 284,089 dated August 28, 1883 but in said patent, and as heretofore constructed, such eyes have been made with 15 the thread inlet as a hole intersecting the longitudinal bore or thread-passage at right angles.

Herein the bevel or incline 15 at the inner 20 end of the passage, leading upward from the bottom thereof to the edge of the inlet 14 farthest from the thread-delivery side-wall of the shuttle, is made for a specific purpose, to wit: to coöperate with and guide the leading end of the threader, now to be described.

25 Referring to Fig. 2 the threader which I prefer to use comprises a ring-like handle or finger-hold 16, an elongated flexible and resilient shank 17, conveniently made of relatively fine spring wire and normally slightly 30 curved longitudinally, and a hook or barb 18 on the free end of the shank. When the free end of the threader shank is inserted in the eye and pushed inward, see full lines Fig. 2, the hook or barb strikes the incline 35 15 and is thereby guided or directed upwardly in an easy manner through the thread-inlet 14, and as the threader is pushed in farther the incline 15 continues to act as a guide upon the shank, so that the hook 18 40 is directed upward through the recess or socket 3 and above the top of the shuttle, as shown in dotted lines. The weaver now takes one or more turns of the thread around the shank below the hook or barb, and pulls 45 the threader backward and out of the eye, thereby drawing the thread into the inlet 14 and through the passage 11, threading the shuttle. Were it not for the guide surface 50 15 the leading end of the threader would be stopped at the closed inner end of the thread-passage, as will be manifest from an inspection of the ordinary type of Thompson eye, and the threader could not be passed through the inlet 14 and upward into position 55 to engage the thread.

The shuttle threading operation is very quickly and easily accomplished by the structure herein shown, and it will also be apparent that the eye can be adjusted relatively to a certain extent to vary the tension 60 on the thread without interfering with the

operation of the guide surface during the threading operation.

In Fig. 3 the eye 20 is externally smooth, and is adapted to be forced with a driving 65 fit into the hole in the shuttle provided for it, but the thread-passage 21 has at its inner end the inclined guide surface 22 leading up to the edge of the inlet or aperture 23, as before, and for the reasons hereinbefore set 70 forth.

Whichever form of delivery-eye be used, and whether made of metal or porcelain, the inlet is at the bottom of the recess or well 3 in the shuttle body, and the guide 75 surface at the inner end of the thread-passage is provided to direct the leading end of a flexible threader up through the thread-inlet of the eye and upward through the recess or well 3 into position to be conveniently 80 brought into temporary engagement with the thread.

Having fully described my invention, what I claim as new and desire to secure by Letters Patent is:—

85

1. A hand-threading loom-shuttle having an upright recess in its body communicating with the bobbin recess, and a transverse delivery-eye fixed in the shuttle-body and having a straight, tubular thread-passage 90 extended thereinto from its outer end and having an inlet at its inner end opening into the bottom of such upright recess, the inner end of the thread-passage being inclined upwardly from the bottom of the passage to the edge of said inlet farthest from the open end of said passage, whereby a guide surface for the leading end of a flexible threader is provided, to direct the same upward through the inlet and into the recess 100 in the shuttle-body when the threader is passed into the thread-passage to thread the shuttle.

2. As a new article of manufacture, a thread delivery-eye for hand-threading 105 loom-shuttles, consisting of a cylindrical, elongated body having a straight, tubular thread-passage extended thereinto from one end and having an inlet near its other end communicating with the passage, the inner 100 end of said passage being inclined upwardly from the bottom of the thread-passage to the edge of the inlet farthest from the open end of such passage, for the purpose set forth.

In testimony whereof, I have signed my 115 name to this specification, in the presence of two subscribing witnesses.

HERBERT L. LITCHFIELD.
